BENJAMIN GRAEMIGER, OF ZURICH, SWITZERLAND, ASSIGNOR TO FIRM AKTIEN-
GESELLSCHAFT DER MASCHINENFABRIKEN ESCHER WYSS & CIE., OF ZURICH,
SWITZERLAND.

COMPRESSOR INSTALLATION.

Application filed April 6, 1923. Serial No. 630,331.

To all whom it may concern:

Be it known that I, BENJAMIN GRAEMIGER, a citizen of the Republic of Switzerland, residing at Zurich, Switzerland, have invented certain new and useful Improvements in Compressor Installations, of which the following is a specification, reference being had therein to the accompanying drawings.

10 The subject matter of the present invention is a compressor installation, comprising at least one main compressor and at least one additional compressor adapted to work in series with the main compressor for the purpose of obtaining a higher pressure.

Compressor installations are often required to deliver periodically an essentially higher pressure than normal pressure, in which case the quantity delivered will of course be smaller than the normal quantity. This is for instance the case with blast-furnace blowing installations which normally work with a discharge pressure of, for instance, 0.8 atmospheres above atmospheric.

20 25 In some cases (hanging of the charge), however, a great increase in the pressure up to double the normal pressure is required, whereby the quantity of air may decrease to a large extent. This manner of working, however, occurs comparatively seldom, so that it is justified to take care that above all the normal working of such installations is as efficient as possible. With compressors running at a constant speed (electromotor

30 35 driven compressors) an increase in pressure above the normal pressure cannot be obtained, unless the compressor is so constructed that it yields a low efficiency at normal working. But also with installations adapted to run at variable speed (turbine driven compressors) turbine and compressor yield a low efficiency at normal working if the compressor is so designed as to be able to discharge periodically at a pressure that is greater than the normal pressure.

40 45 In order to respond to the above mentioned requirements without having to put up with the drawbacks referred to, the additional compressor of an installation of the aforementioned type working in series with the main compressor is driven according to the present invention by a prime mover in which expands that part of the medium de-

livered by the main compressor which does not enter into the additional compressor. The main compressor of such an installation may be so designed as to give the most favourable results at normal working. Likewise the engine driving the main compressor may be built to yield the highest efficiency at normal working. The engine driving the additional compressor is simple and cheap. The work is, after all, performed by the well equipped and normally loaded engine driving the main compressor.

The additional compressor may be designed as a centrifugal compressor or as a piston compressor. In the first case the prime mover driving the additional compressor is preferably a turbine and in the second case a piston engine.

Constructional examples of the subject matter of the present invention are illustrated on the accompanying drawings, in which:

Fig. 1 shows in a diagrammatic manner a first constructional example.

Fig. 2 shows a diagram illustrating the manner in which an installation according to the present invention operates.

Fig. 3 shows part of the construction of an additional compressor and of the power engine driving the former.

Figs. 4 and 5 show diagrammatically a second and a third constructional example respectively.

The installation illustrated in Fig. 1 comprises a centrifugal compressor acting as main compressor 1, which is driven by a power engine 2 of any suitable type. The medium sucked by the compressor 1 through the conduit 3 may be delivered into a conduit 4 in which a valve 5 is provided. 6 denotes an additional compressor driven by a power engine 7. To the pressure conduit 4 a conduit 8 is connected which divides itself at its one end into two branches 9, 10 of which the branch 9 may be used for supplying medium delivered by the compressor 1 to the power engine 7 and the branch 10 is adapted to supply that medium to the additional compressor 6. The connection between the conduits 4 and 8 is controlled by a valve 11. The motive fluid supplied to the power engine 7 is discharged from the latter through a conduit 12. The medium, the pressure of which has been raised in

the additional compressor 6 is discharged into a conduit 13, the connection between the latter and the conduit 4 being controlled by a valve 14.

5 During the normal working the valves 11 and 14 are closed, whilst the valve 5 is open. The main compressor 1 delivers then into the conduit 4 through which the compressed medium is supplied to the consuming place 10 or places.

When an increase in the pressure is required, the valve 5 is closed and the valves 11 and 14 are opened. The main compressor 1 discharges now into the conduit 8 which 15 distributes the medium between the power engine 7 and the additional compressor 6. The latter is now connected in series with the main compressor. The pressure of that part of the medium delivered by the main 20 compressor 1 and passing through the additional compressor 6 is increased to the required height. The manner of working will be understood from the diagram illustrated in Fig. 2, in which volume-pressure diagram 25 n shows the characteristic of the main compressor running at the constant speed n . The steep curve a shows the combined working of the main compressor and the additional compressor. This curve is obtained 30 by superposing the volume-pressure characteristics of the main compressor and of the additional compressor and by taking into account the output obtained from the medium expanding in the driving engine for 35 the additional compressor, (in which case the additional compressor is also a centrifugal compressor and the respective driving engine is a turbine).

To each point of the steep curve a a determined point of the curve n corresponds. If, for example, the point Q_2, p_2 corresponds to the maximum pressure required, the parts of the installation may be so chosen that to that point the point Q_1, p_1 of the main 40 compressor corresponds whereby this point represents the normal load of the main compressor. In order to obtain a quantity Q_2 delivered at the required maximum pressure that is as large as possible, the corresponding point Q_1, p_1 may be shifted into the overload range of the main compressor, whereby the capacity of the driving engine to be able to work even when overloaded is made use of. This is the more advisable as generally 45 the maximum pressure and thereby the overload is only required during a comparatively short time. If the engine driving the additional compressor admits a variation of its speed, the latter may be so increased beyond 50 the normal speed in order to obtain the required maximum pressure that the service conditions for the point which corresponds to normal load are not materially prejudiced. In this case the characteristic n in 55 Fig. 2 corresponds to the highest permissible

speed of the main compressor. All points Q, p below the curves n and a are possible working points.

It lies in the nature of the whole installation that during the working of the additional compressor an automatic adjustment of the speed within comparatively wide limits takes place according to the resistance at the place of consumption.

As is shown in Fig. 1, the part of the conduit 4 between the centrifugal compressor 1 and the valve 5 may be provided with a blow off valve 15. A blow off valve 16 may further be inserted in the conduit 13 between the additional compressor 6 and the valve 14.

With the constructional example illustrated in Fig. 3 the additional compressor 6 is constructed as a centrifugal compressor and the power engine 7 driving the latter is 85 constructed as an air turbine. The compressor and the turbine are provided with one inlet branch 17 common to both. The delivery branch 18 of the additional compressor 6 is arranged on one side and the discharge branch 19 of the air turbine 7 is arranged on the other side of the unit 6, 7 which is enclosed in one casing.

Two or more main compressors constructed as centrifugal compressors may be arranged to work into one pressure conduit common to both in case an absolute reliability in the working of the installation is required as is particularly the case with compressor installations for blast furnaces. In 100 Fig. 4 a second main compressor 20 is indicated, which is adapted to work into the same pressure conduit 4 as the main compressor 1 and to which the same additional compressor 6 appertains as to the main compressor 1. In this case separate valves 21, 22 have to be provided which permit of disconnecting the centrifugal compressor 1 or the centrifugal compressor 20 respectively from the pressure conduit 4 when the respective compressor is not operative. Assuming, for instance, the centrifugal compressor 1 to be out of order and a higher pressure than the normal pressure to be required, then the valve 21 is closed and the valve 22 is opened. The valve 5 is closed and the valves 11 and 14 are opened, the compressor 6 works now in series with the compressor 20. If, on the other hand, normal pressure has to be produced and the centrifugal compressor 1 is 110 shut down, only the valves 5 and 22 are opened and the valves 21, 11 and 14 are closed.

Between the valve 21 and the pressure conduit 4 a blow off valve 30 may be arranged and between the valve 22 and the pressure conduit 4 a blow off valve 23 may be inserted.

As is shown in Fig. 5, the medium delivered by the main compressor 1 may be

caused to pass a cooling device 24 previous to its entering the additional compressor 6 which device is provided with a coil 25 through which cooling water flows. On the other hand the portion of the medium that is used as motive fluid in the prime mover 7 may be heated previous to its expanding, for which purpose a device 26 may be provided, through which a heating coil 27 passes.

10 The additional compressor or the plurality of such compressors may be constructed as piston compressors, in which case the prime movers driving the additional compressors are preferably also piston engines.

15 I claim:

1. A compressor installation, comprising in combination, at least one main compressor, an additional compressor adapted to work in series with said main compressor 20 for the purpose of obtaining a higher pressure, and a driving engine for said additional compressor driven by that portion of the medium compressed in the main compressor which does not enter the additional 25 compressor when working in series with the main compressor.

2. A compressor installation comprising in combination, at least one main compressor, an additional compressor, means interposed between said compressors and adapted to conduct the compressed medium so that the additional compressor may work in series with the main compressor, and a driving engine for said additional compressor 35 connected up to said conducting means so that the portion of the medium compressed in the main compressor which does not enter the additional compressor expands in said driving engine.

40 3. A compressor installation comprising in combination, at least one main compressor, an additional compressor of the centrifugal type, means interposed between said compressors and adapted to conduct the compressed medium so that the additional compressor may work in series with the main compressor, and a driving engine of the turbine type for the additional compressor connected up to said conducting means so that the portion of the medium compressed in the main compressor which does not enter the additional compressor expands in said driving engine.

45 5. A compressor installation comprising in combination, at least one main compressor, an additional compressor, means in-

terposed between said compressors and adapted to conduct a portion of the medium compressed by the main compressor to said additional compressor so that the latter 50 may work in series with the former, a cooling device interposed in said conducting means, a driving engine for said additional compressor, and means adapted to conduct that portion of the medium compressed by 55 the main compressor which is not dealt with in the additional compressor to said driving engine.

5. A compressor installation comprising in combination, a main compressor, an additional compressor, means interposed between said compressors and adapted to conduct a portion of the medium compressed by the main compressor to said additional compressor so that the latter may work in 70 series with the former, a driving engine for said additional compressor, means adapted to conduct that portion of the medium compressed by the main compressor which is not dealt with in the additional compressor 75 to said driving engine, and a heating device interposed in said conducting means.

6. A compressor installation having at least one main compressor, in combination with a compressor in series therewith and an engine driven by medium compressed by said main compressor, heating means between said engine and main compressor and cooling means interposed between the two compressors.

7. A compressor installation having at least one main compressor, in combination with an additional compressor receiving compressed medium from said main compressor, cooling means interposed between the compressors, and an engine for driving said additional compressor driven by compressed medium from said main compressor.

8. A compressor installation having at least one main compressor, in combination with an additional compressor, receiving compressed medium from said main compressor, cooling means for the medium delivered to said additional compressor, an engine for driving said additional compressor operated by medium from said main compressor and heating means to heat the driving medium received by said engine.

In testimony whereof I affix my signature.

BENJAMIN GRAEMIGER.
